UNITED STATES PATENT OFFICE.

CHARLES N. BUTLER, OF PHILADELPHIA, PENNSYLVANIA, ASSIGNOR TO
DURKIN CONTROLLER HANDLE COMPANY, OF PHILADELPHIA, PENN-
SYLVANIA, A CORPORATION OF PENNSYLVANIA.

CONTROLLER-REGULATOR.

No. 826,474.

Specification of Letters Patent.

Patented July 17, 1906.

Application filed December 16, 1905. Serial No. 292,010.

To all whom it may concern:

Be it known that I, CHARLES N. BUTLER, a citizen of the United States, residing at Philadelphia, in the county of Philadelphia and 5 State of Pennsylvania, have invented certain Improvements in Controller-Regulators, of which the following is a specification.

This invention relates to mechanism designed for regulating the movements of controllers in admitting current to motors, so that the operators cannot overload the motors, destroy the apparatus, or waste current.

The leading object of the invention is to provide an improved construction of simple 15 and inexpensive character, not readily tampered with, and protected from the weather, while securing a retarded or step-by-step movement in throwing on the current and permitting the mechanism to be turned back 20 to the initial position to throw off the current without retardation.

In the accompanying drawings, Figure 1 is a sectional elevation representing a form of the invention. Fig. 2 is a sectional view of 15 details of construction, taken transversely to the section shown in Fig. 1. Fig. 3 is a bottom view of a section of the hood and its connections. Fig. 4 is a vertical sectional view representing a second form of the invention; 25 and Fig. 5 is a sectional view of a part of the construction shown in Fig. 4, taken transversely thereto.

As shown in the drawings, the controller-shaft 1, projecting through and revolving in 5 the casing-top 2, has fixed thereon a cylindrical hood 3, which is engaged and revolved by the handle 4.

As shown in Figs. 1, 2, and 3, peripheral lugs or stops 5 are formed at proper intervals 5 within the hood, and depending from the top of the hood, between the center and the periphery, are fingers 6, pivoted by means of pintles 7 passing therethrough and through the supporting-lugs 8. The respective fingers have the tops thereof provided with the rounded portions 9 and the square portions 10, by which they are permitted to oscillate freely in one direction from the vertical position, in which they normally hang, while they are prevented from oscillating substantially beyond the vertical position in the other direction, the lower parts of the respective fingers being suitably, though not es-

sentially, provided with the inclined surfaces 11 on the opposite sides of the centers of 55 oscillation from the shoulders 10.

Fixed to the top of the casing 2 is a bearing 12, upon which is fulcrumed intermediate of its length a dog 13 by means of the pintle 14, the outer end of the dog in its normal position being held down by gravity beneath the stops 5 and the inner end being up in the path of the fingers 6.

When the handle is revolved to revolve the hood and the shaft for the purpose of turning on current, the fingers 6 successively engage the inner end of the dog (suitably provided with the inclined contact-surface 6') and tilt it so that the outer end lies in the path of the stops 5. Each finger tilts the 70 dog so that it is engaged by the advancing stop corresponding thereto to check the rotation, and the dog drops out of engagement with the stop when the pressure on the handle is released, the successive actions compelling a regulated or step-by-step forward movement. In the reverse movement, the fingers swing back, riding over the end of the dog in their path, and the mechanism is reversed without engagement of the stops or 75 retardation, the outer end of the dog being suitably provided with the inclined surface 6'', whereby a positive engagement cannot be effected with the stops in the reverse movement. 85

As shown in Figs. 4 and 5, the cylindrical part of the hood is provided with the interior flange or ring 15 and the inclined fingers 16, fulcrumed on the pintles or bearings 17, the free ends of the fingers normally resting on 90 the flange, from which such fingers are inclined upwardly in the direction of the corresponding stops or lugs 5. Fixed to the top 2 is a bearing 18, in which is fulcrumed a dog 19 by means of a pintle 20. This dog has its 95 free end resting normally on the ring 15, its outer end with the inclined surface 19' riding up the fingers into engagement with the stops, from which they drop by gravity in turning on the current, while resting on the 100 flange and having the fingers pass over it in the reverse movement. As in turning on the current the dog is engaged by the successive inclined finger of the revolving hood and carried up the inclined planes thereof, so 105 that it is engaged by the corresponding stops,

from which they drop by gravity when the pressure on the handle is relieved, and as in turning on the current the dog passes freely under the oscillating fingers, the forward movement is regulated to a step-by-step action, while the rearward movement is uninterrupted.

Having described my invention, I claim—

1. A controller-regulator comprising, in combination with the controller-shaft, a revolving device fixed to said shaft and having thereon stops and fingers movable relatively to said stops, in combination with an oscillating dog having a stationary support.
2. A controller-regulator comprising a revolving hood having stops and fingers depending therefrom, in combination with a fulcrumed dog thrown by said fingers into the path of said stops.
3. A controller-regulator comprising, in combination with a controller-casing and shaft, a hood fixed to said shaft and having stops and fingers thereon, a bearing fixed to said casing, and a dog fulcrumed on said bearing, said dog being tilted by said fingers to engage said stops.
4. A controller-regulator comprising, in combination with a stationary part and a revolving shaft, a hood fixed to said shaft, said hood having fixed stops and fulcrumed fingers therein, and a dog having a fulcrumed

connection with said stationary part, said dog automatically disengaging said stops.

5. A controller-regulator comprising a hood, a series of stops, a series of oscillating fingers having a free motion in one direction and means for restricting their motion in the other, and an oscillating dog thrown by said fingers into engagement with said stops in turning on the current and freely passing said fingers in turning off the current, said dog being automatically disengaged from said stops.

6. A controller-regulator comprising a dog fulcrumed intermediate of its length, a series of stops and a series of fingers, said fingers engaging one end of said dog to throw the other end thereof into the path of said stops.

7. A controller-regulator comprising a dog fulcrumed intermediate of its length, a series of stops, a series of fingers engaging one end of said dog to throw the other end into the path of said stops, said dog being automatically disengaged from said stops.

In testimony whereof I have hereunto set my hand, this 11th day of December, A. D. 1905, in the presence of e. subscribing witnesses.

CHARLES N. BUTLER.
